(57) CLAIM

The ornamental design for a combination baby poncho jacket, car seat cover, and shopping cart liner, as shown and described.

DESCRIPTION

FIG. 1 is a front perspective view of the subject design, taken from above;

FIG. 2 is a rear perspective view thereof, taken from below;

FIG. 3 is a left side view thereof;

FIG. 4 is a front elevational view thereof;

FIG. 5 is a right side view thereof;

FIG. 6 is a rear elevational view thereof;

FIG. 7 is a top plan view thereof;

FIG. 8 is a bottom plan view thereof; and,

FIG. 9 is a perspective view of the subject design shown deployed as a shopping cart liner.

The broken line showing of a shopping cart is included for the purpose of illustrating environment and forms no part of the claimed design.
